US0D1106463S

(12) **United States Design Patent** (10) **Patent No.:** **US D1,106,463 S**
(45) **Date of Patent:** **** Dec. 16, 2025**

(54) **MULTIUSER BIOFEEDBACK DEVICE**

(71) Applicant: **Empatica Srl**, Milan (IT)

(72) Inventors: **Matteo Lai**, San Sperate (IT); **Riccardo Sirtori**, Milan (IT); **Florian Timm Boje**, Milan (IT); **Cristiana Picco**, Milan (IT); **Claudio Santucci**, Milan (IT)

(73) Assignee: **Empatica Srl**, Milan (IT)

(**) Term: **15 Years**

(21) Appl. No.: **29/840,580**

(22) Filed: **May 31, 2022**

(51) **LOC (15) Cl.** **24-02**

(52) **U.S. Cl.**

(57) **CLAIM**

The ornamental design for a multiuser biofeedback device, as shown and described.

DESCRIPTION

FIG. 1 is a perspective view of the multiuser biofeedback device;

FIG. 2 is a front view thereof;

FIG. 3 is a top view thereof; and,

FIG. 4 is a bottom view thereof.

The broken lines in the drawings illustrate portions of the multiuser biofeedback device that form no part of the claimed design.
